UNITED STATES PATENT OFFICE.

LYDIA A. TYLER, OF SPOKANE, WASHINGTON, ASSIGNOR TO R. J. SCHMID, OF SAN DIEGO, CALIFORNIA.

HAT-VENTILATOR.

1,111,417.

Specification of Letters Patent. Patented Sept. 22, 1914.

Application filed February 14, 1914. Serial No. 818,749.

To all whom it may concern:

Be it known that I, LYDIA A. TYLER, a citizen of the United States, residing at Spokane, in the county of Spokane and State of Washington, have invented certain new and useful Improvements in Hat-Ventilators, of which the following is a specification, reference being had to the accompanying drawings.

This invention is an improved hat ventilator for keeping the head of the wearer cool, the object of the invention being to provide an improved device of this character which may be readily attached to and used in any ordinary hat, and especially in hats which are provided with ventilating openings.

In the accompanying drawings—Figure 1 is a perspective view of a hat provided with a ventilating device constructed in accordance with my invention, a portion of the crown of the hat being removed so as to disclose the ventilating device. Fig. 2 is a detail perspective view of the ventilating device showing the same detached from the hat.

In accordance with my invention, I provide a flexible bar 1, which may be made of spring metal or any other suitable material, and is capable of being bowed and placed in the crown of a hat so as to extend across the same. The ends of the bar are inserted between the hat and the sweat band. The bar,

owing to its being made of spring material, by its own elasticity, maintains itself in place in the crown of the hat. From the center of the bar is suspended a fan 2, by means of links 3, the said links being here shown as provided with eyes at their ends engaged with openings near the upper edge of the fan, and also engaged with eyes 4, with which the bar is provided. The hat A is preferably provided with ventilating openings 5. The motion of the wearer of the hat causes the fan to swing so as to maintain a circulation of air in the crown of the hat, and hence greatly promote the comfort of the wearer, and also greatly lessen liability of sunstroke.

I claim:

1. A hat ventilating device comprising a bar adapted to be placed in the crown of a hat, a fan, and links suspending the fan from the center of the bar for swinging movement of the fan.

2. A hat ventilating device comprising a spring bar adapted to be arched and placed in the crown of a hat, a fan, and links suspending the fan from the center of the bar for swinging movement of the fan.

In testimony whereof I hereunto affix my signature in the presence of two witnesses.

LYDIA A. TYLER.
